CLAIM

We claim the ornamental design for a cowlingless goalie skate for an ice hockey goalie, as shown and described.

DESCRIPTION

FIG. 1 is a perspective view of a cowlingless goalie skate for an ice hockey goalie in accordance with the design;

FIG. 2 is a lateral side elevation view of the cowlingless goalie skate of FIG. 1;

FIG. 3 is a medial side elevation view of the cowlingless goalie skate of FIG. 1; and,

FIG. 4 is a front end view of the cowlingless goalie skate of FIG. 1.

The broken lines shown are included for the purpose of illustrating portions of the article which form no part of the claimed design.
